UNITED STATES PATENT OFFICE.

LUDWIG MAUTNER, OF VIENNA, AUSTRIA-HUNGARY.

PNEUMATIC AND ELECTRIC CLOCK SYSTEM.

SPECIFICATION forming part of Letters Patent No. 271,347, dated January 30, 1883.

Application filed October 16, 1880. (No model.) Patented in Belgium August 17, 1880, No. 52,160; in France September 20, 1880, No. 137,982; in Italy September 20, 1880, XIV, 12,175, and XXIV, 248; in Austria-Hungary September 23, 1880, No. 21,944 and No. 23,901; in Sweden October 16, 1880; in Denmark December 13, 1880, No. 1,598; in Spain January 1, 1881, No. 1,038, and in Germany August 16, 1881, No. 14,067.

To all whom it may concern:

Be it known that I, Dr. LUDWIG MAUTNER, Knight of Markhof, of Vienna, in Austria-Hungary, have invented a new and useful mechanism for automatically and isochronously working, regulating, and winding up a series of clocks within a circuit from a standard clock, which I have termed "Orthochronophor," of which the following is a specification.

10 The invention consists in the construction and operation of mechanism and combination of mechanisms whereby hydrostatic, pneumatic, and electric power are made to co-operate to produce the following results: first, the automatic winding up of one or more or all of a series of clocks arranged in a circuit by means of hydropneumatic power—that is to say, the maintaining of such clock or clocks in continuous operation automatically; second, to automatically regulate one or more or all of a series of clocks within a circuit at a predetermined time and at any distance from each other by means of hydropneumatic power through the medium of an electric current influencing an electro-magnet that serves to set in operation the hydropneumatic mechanism in such a manner that a difference, whether it be a gain or loss of time, can never occur; third, to automatically regulate and wind up, through the medium of a standard clock, a series of secondary clocks within a circuit and at any distance from each other and said standard clock, at a predetermined time, by means of hydropneumatic power and electricity made 35 to actuate suitable mechanism, all as hereinafter described in detail and shown in the accompanying seven sheets of drawings, in which—

Figure 1 represents in elevation a general view, partly in section, of my regulating and winding-up mechanisms as combined with the clock-movement. Fig. 1^a shows the clock-movement with part of the regulating and winding-up mechanism. Fig. 2 is an elevation, and Fig. 3 a plan view, of the mechanism 45 for actuating the winding-up devices. Figs. 4 and 4^a are front and side elevations, respectively, of the winding-up mechanism, the latter partly in section. Fig. 4^b shows said mechanism in perspective, and Figs. 4^c and 4^d are like

views of the pawls *q p* thereof. Fig. 4^e is a detail view of the devices for maintaining the train of gearing in motion during the winding of the clock. Fig. 5 is a plan view of the clock-movement. Figs. 6 and 6^a are front and side elevations, and Fig. 7 a plan view, of the mechanism for actuating the regulating devices. Figs. 8, 8^a, and 9 are detail views of part of the regulating devices, and Fig. 16 is a like view of part of the winding-up mechanism. Figs. 10 and 12 represent in elevation, and Fig. 11 by a plan view, the electro-pneumatic relay with the three-way slide-valve. Figs. 13, 14, and 15 show the regulating and winding-up mechanism for secondary clocks in its various positions.

Like letters refer to similar parts wherever such may occur.

The clock-movement, the regulating and winding-up devices, and the mechanism for actuating said devices are all mounted in a suitable frame, A; and that my invention may be better understood I will first describe the winding-up mechanism, its combination with a standard-clock movement, and its actuating devices, as well as the manner in which said winding is effected, referring more particularly to Figs. 1, 1^a, 2, 3, 4, 4^a, 5, 6, 6^a, 7, 8, 8^a, and 16.

1 represents the pendulum, carrying the weight 2; and 3 is the arbor that carries at its upper end a coupling, 4, through which the movements of said arbor are communicated directly to the usual mechanism that actuates the hands, which latter are mounted on top of the column. The arbor 3 carries, also, a regulating wing or hand, 7, below the coupling 4, that moves synchronously with the minute-hand. The regulating-wing has one of its extremities enlarged in the form of a sector, and when said wing is in a position to be actuated by the regulating devices, as hereinafter explained, its enlarged end rests upon a roller, 8, that is pivoted to an arm projecting from the main frame A. The enlarged wing end slides upon this roller during the time the regulating devices are in operation, to avoid all lateral pressure upon the minute-arbor, that would otherwise result from the action of said devices. Below said regulating-wing 7, the shaft

3 carries a cam-faced wheel, 5, upon which ride together the roller 10, pivoted on a pin projecting from the upper enlarged end, 9, of a rod, 12, and a prism, 11, secured to said rod 5 end 9 by the side of the roller.

The rod 12 is provided at its lower end with a projecting abutment or nose, 13, Fig. 2, that serves to disengage the mechanism for actuating the winding-up devices. This mechanism, 10 Figs. 2 and 3, consists of a lever, 14, that carries at its forward socketed end a bent arm, terminating in a prism, 15, adjustably secured thereto by a set-screw, y, and in rear of this socketed end the lever carries a weight, 16, 15 suspended from a rod, R. On a shaft, S, turning loosely in its bearings in the standard s, is rigidly mounted a two-armed escapement-lever, 18, having inwardly-projecting pallets 17 and 17½, respectively, which govern the movements of the lever 14, and upon said shaft S is also rigidly mounted a lever, 19, the rear or free end of which carries a weight, 22, and at or near its center said lever is provided with a projecting pin, 20.

25 Upon a standard, S', is pivoted a pawl, 21, whose engaging face or nose lies in the path of the abutment 13 on rod 12. The downward movement of said pawl is limited by a pin, 23. Upon the shaft of the lever 14 is mounted 30 a weighted lever, 25, the lateral movements of which are limited by the pins s' s², projecting from the segment S². The hub 24 of said lever is provided with a segmental guide-slot, with which engages a pin, 26, projecting from 35 lever 14. Within the air-cylinder is located a bellows-shaped or other compressing device or piston connected with a rod, 37, terminating in or carrying a toothed rack-bar.

The rod 37 is provided with a projection, 38, 40 for a purpose presently explained, and also with a stop, 44, to limit its downward movement in the supporting-bracket, within which said rod reciprocates.

The rack-bar meshes with a pinion, 41, 45 loosely mounted on the shaft 40 of the winding-up drum O, in proximity to the pinion 41, and rigidly connected with shaft 40 is mounted a cam, 45, with which engages a pawl, 42, actuated by a spring, 43, pivoted to the face 50 of the pinion 41, and serves to lock the pinion to the winding-up shaft.

In order to permit the free unwinding of the cord from the drum O, the pawl 42 is held out of engagement with the cam 45 by means of 55 a two-armed angular lever, q, pivoted at its angle to the guide-bracket X, and the lateral motion of said lever is limited by a set-screw, x, Fig. 4, to regulate and insure the engagement of said lever with the pawl. A connecting-rod, 39, has one end pivoted to the lever 14, and its other looped end is loosely connected with the rack or rod 37. A pipe, 34, connects the pipe p, between the cylinder B C, with a piston-cylinder, D. To the upper end 65 of its piston-rod 35 is pivoted a lever, 36, fulcrumed at r' upon the main frame. The lever

36 carries at its outer or free end a weighted pawl, r r². (Shown in dotted lines, Figs. 1^a and 5, and in full lines in Fig. 4^e.) The pawl r² r is in a position to engage the toothed wheel P 70 of the train of gearing, and impart motion to said wheel during the winding up of the clock, in the manner and for purposes hereinafter explained.

The operation of the mechanism just described to automatically wind up a clock (which I prefer to effect every hour) is as follows: The cam-faced wheel 5 on shaft 3 is so arranged that the highest point, 6, of its incline lies underneath the minute-hand and follows its rotation, the movement of both being synchronous, and the relative position of the hand and the point 6 are always coincident, while the arrangement of the roller 10 and prism 11 is such that when the minute-hand indicates the hour the prism will lie upon said point 6 of the cam 5. The gradual ascent, during the rotation of cam 5, of the roller and prism up the incline of the cam slowly raises the rod 12 until its projection 13 comes 90 in contact with the pawl 21 and carries said pawl with it to lift the lever 19, through the medium of its pin 20, and tilt the escapement-lever 18 forward to release the prism 15 from pallet 17, and bringing the pallet 17½ into engagement with said prism. This downward movement of the prism and its lever partially tilts the weighted lever 25 from right to left, Figs. 2 and 3, so as to bring it at or near its dead-point, and the moment the prism 11 has 95 passed the point 6 on cam 5 and falls down to the lowest point of the incline a corresponding downward movement of the rod 12 takes place, thereby disengaging pawl 21 from projection 13, causing a downward movement of lever 19 under the impulse of its weight 22, and a corresponding backward movement of the escapement-lever 18, thereby disengaging the prism 15 from pallet 17½, permitting it to move down 100 between the two pallet-arms. The corresponding movement of lever 14, under the impulse of its weight 16, instantaneously carries the lever 25 toward the left, over its dead-point, and, through the medium of its weight, onto the pin s'. This movement of the lever 25 rotates 105 the three-way valve 30, through the medium of the pin 28 and valve-lever 29, to establish communication between the supply-pipe 111 and a pipe, 32, communicating with fluid-cylinder B, admitting water thereto, that serves 110 to compress the air therein, as well as in the cylinder C, which compressed air serves to raise the rod 37. The upward movement of the latter releases the pawl 42 from the lever q, and through the spring 43 said pawl is 115 thrown into engagement with the nose of the cam to lock the pinion to shaft 40 and wind up the cord carrying the weight W' upon drum O. At the same time compressed air passes 120 from pipe p into pipe 34, and thence to the piston-easing D, raising its piston, and, through 125 its rod 35 and lever 36, throws the pawl r² into

130 its rod 35 and lever 36, throws the pawl r² into

engagement with the toothed wheel P of the clock-movement, to rotate said wheel while the cord is being wound up, this arrangement being necessary; otherwise the clock would stop 5 during the winding up, this being effected in a direction opposite to that of the train of gearing. The operation of this auxiliary power is more clearly shown in Fig. 4^e, the arrow x^5 indicating the direction of rotation of the winding-drum, 10 and the arrow x^6 that of the gear-wheel P of the train of gearing. As soon as the winding of the clock commences—that is to say, as soon as compressed air is delivered from the cylinder B to the cylinder C to move the rack-bar—a portion of this compressed air passes 15 from pipe p into pipe 34 and cylinder D, as above stated, to move the piston-rod upward and the free end of the lever with the pawl r^2 downward. The weighted arm r of said pawl, bearing upon the lever, cannot turn on its pivot, 20 and the end of the pawl, being engaged with one of the teeth of the wheel P, will carry it along, the pawl remaining in contact with the tooth first engaged until it has described a given 25 arc of a circle which is equal to the distance traveled by the winding-up drum to wind the clock. On the descent of the piston-rod, effected as hereinafter explained, the pawl-arm r will, however, be tilted toward the wheel P, 30 and the pawl will ride freely over the teeth of said wheel. As the clocks are wound up every hour, the distance traveled by the pawl and winding-drum will necessarily be a limited one. Before the cord is fully wound up the projection 38 on rod 37 will engage the loop of the 35 rod 39, carrying said rod upward, and with it the lever 14, thereby slowly reversing the weighted lever 25 until said lever is about to pass its dead-point, when the clock will be 40 practically wound up, and a slight further upward movement of the rod 39 and lever 14 will carry lever 25 over its dead-point, and said lever will be instantaneously thrown over on the stop s^2 , thereby reversing the three-way 45 valve 30, through the medium of pin 27, and the valve-lever 29 cutting off communication between supply-pipe 111 and the connecting-pipe 32, and establishing communication between the latter and the waste-pipe 27^a to exhaust the water from cylinder B. This escape 50 of the water will cause the rack-bar 37 to move downward into its normal position, determined by the stop 44 coming in contact with a set-screw, x' , passing through a bearing at the lower end of the guide X, the upward movement 55 of the rack-bar being limited by set-screw x^2 at the upper end of said guide. By means of these set-screws the movements of the rod 37 may be adjusted with nicety. The 60 downward movement of the rack-bar rotates the pinion 41, with its pawl 42, backward until the pawl-arm p' comes in contact with the horizontal arm of the lever q, pressing it downward, and thereby disengaging the pawl from 65 the cam, the vertical arm of said lever going back to its normal position on the point of the set-screw x , thereby permitting the free unwinding of the cord from the drum O. The escape of the water from cylinder B, and consequent exhaust of compressed air in cylinders 70 D B, causes the piston to fall back into its normal position and retract the pawl r^2 from the teeth of the wheel P.

It will be readily understood from the above description that the winding up of the standard clock is effected at the expiration of every hour, whether the clock be fast or slow, that this winding up is dependent upon the regulating devices when the clock is slow and independent thereof when said clock is fast. 75

I will now proceed to describe the regulating mechanism, referring more particularly to Figs. 1, 1^a, 6, 6^a, 7, 8, 8^a, and 9. This mechanism consists of an electro-magnet, T, connected by wires 81 and 82, respectively, with the + 80 and - poles of a battery located at an observatory or other point from which the true time is obtained. The armature-lever 50 carries at one end a pivoted pawl, 51, from the sides of which projects a pin, o, and at its other end it 85 is connected to a retracting-spring, 112. The pawl 51 engages a ratchet-disk, 52, prevented from rotating backward by a weighted pawl, 53, having a laterally-projecting arm, 54.

Upon the ratchet-shaft is mounted an eccentric, 55, upon which rides the lower end of a lever, 56, pivoted at n^2 to an arm projecting from the shaft-support N'. The upper end of this lever carries a prism, 57, with which engages the outer end of the lever 58, pivoted 90 at n^3 in a standard, N³. Said lever carries a weight, 80, and a pin, 59, that works in a segmental slot, 60, in the rear horizontal arm of a three-armed lever, Q, the forward horizontal arm, 62, of which terminates in a segment provided with two pins, 63 and 64, that alternately engage with a lever, 65, of a three-way valve, 66, interposed in pipes 68 and 69 and the supply-pipe 111, above mentioned. The pipe 68 is connected with the fluid-cylinder E, 95 which latter is connected by pipe e' with the air-cylinder F, containing a compressible or other piston-like cylinder, C, above described, the piston-rod 70 of which is connected with the regulating-fork 71 and the tumbling or 100 throwing-out mechanism $i j k m n$, hereinafter more fully described. A rod, 72, is connected at one end with the piston-rod 70, and, extending downward, is pivoted at its lower end to the lever 58. A second rod, 73, hung upon 105 the same pivot with rod 72, extends downward through a guide-bracket, a', and terminates in a rectangular arm, a², provided with a bearing for a vertical rod, 74, provided at its lower end with bosses or sleeves b' b', adjustably secured thereto by set-screws. The rod 74 passes through a guide-bracket, a³, 110 and terminates in an enlarged slotted or forked head, h, for the reception of a pin on the free end of a segmental lever, 75. This latter lever is pivoted upon the standard N' at its rear 115 end and carries about midway a spring-pawl,

76, adapted to engage a laterally-projecting pin or arm, 77, on the weighted pawl L L², having the pawl or engaging faces 78 79.

By means of the mechanism just described 5 a standard clock may be regulated by means of electricity from an observatory, or through the medium of a standard clock at the observatory or other point a series of secondary clocks within a circuit may be regulated, and 10 this is effected as follows: If a standard clock is to be regulated from an observatory or other time-indicating station, the wires 81 and 82 are connected with the poles of a battery at said station, from which the time at meridian 15 is to be obtained. An operator at said station alternately closes and breaks the circuit twelve times, the first taking place twenty-two seconds before twelve o'clock, the others succeeding at intervals of two seconds. At each 20 closing of the circuit the armature-lever 50 is attracted, and when the current is interrupted the spring 112 retracts the lever, and, through the pawl 51, rotates the ratchet-wheel 52 one tooth, the pawl 53 preventing its retrograde 25 movement. The ratchet-wheel and eccentric 55 being mounted on the same shaft, the latter is consequently rotated step by step at each closing and breaking of the circuit, thereby gradually swinging the lever 56 on its ful- 30 erum. At the last interruption of the circuit the prism 57 moves from under the lever 58, which is instantaneously carried down by its weight 80, and through the medium of its pin 59 in slot 60 of lever Q the rear arm of said lever 35 is carried down with the lever 58, and the forward arm thrown upward under the impulse of the weighted arm 61, which moves from pin s³ to pin s⁴, Fig. 6, and, through the pin 64, engaging lever 65, the three-way valve is instantaneously turned, thereby establishing communication 40 between the feed-pipe 111 and the pipe 68, connected with cylinder E, admitting water thereto and forcing the air therein into cylinder F to raise the piston, with its rod and the 45 regulating-fork. The downward movement of the lever 58 carries with it the rods 72 and 73, and through rod 74 the free arm of the segment-lever 75, to bring the pawl 76, through 50 the impulse of its spring, under the pin 77, as shown in the secondary clock, Fig. 13. The 55 rod 70 is now moved upward by the air compressed in cylinder F through the influx of water in E, and the regulating-fork 71 is carried into position to catch the regulating-wing 7, Figs. 1, 1^a, 5, and 8, bringing it exactly upon a central line, thereby moving the hands to 12, whether the clock be slow or fast, the extent of divergence of the outer extremities of the arms of the fork being regulated so as to catch the 60 wing at any point within three, four, or even five minutes of its true position. As soon as the fork 71, which is pivoted to the upper end of the piston-rod 70, has nearly reached the limit of its upward movement, the stop-arm i comes in 65 contact with the hooked end of a weighted rod, j, and a slight further movement of the fork in that direction tilts the latter backward and

outward over the rod, out of the way of the regulating-wing 7, and the catch K, closing onto the arm i, holds the fork 71 in that position, and the rod 70 is thus capable of a further upward movement, and continues so to move until the adjustable collar l on the said rod comes in contact with the loop l', Fig. 1, on the upper end of rod 72, to lift the latter, 75 the lever 58, and the rod 73, and through the latter the rod 74 and segment-lever 75, whose pawl 76, being in engagement with the pin 77, as above described, lifts the weighted pawl L L² also, until the inclined faces 78 79 of its 80 arms come successively in contact with the pin o and the arm 54 on the pawls 51 53, respectively, to disengage both the pawls almost simultaneously from the ratchet 52, to enable it to return into its normal position under the 85 action of a spiral spring (not shown in the drawings) of said ratchet. This return movement of the ratchet causes a corresponding movement of the eccentric 55 and lever 56, which moves back to bring its prism 57 in 90 position to support the lever 58. The upward movement of the rod 70 and parts connected therewith continues, and said rod carries with it the hooked and weighted rod j, through the medium of the laterally-projecting arm m, until the pawl 76 has reached a point which causes it to slip from under the pin 77, projecting from the lower vertical weighted arm, L², of the pawl L, (said pawl having its pivotal point on the lever sufficiently out of line 100 with the pin to effect this,) to bring said lever into its normal position, as shown in Fig. 6. Before the water flowing into cylinder E can reach the cylinder F the pin 59 on lever 58, working in segment 60 of the lever Q, will have 105 tilted said lever so far as to bring the weighted lever over its dead-point, and, falling back upon stop s³, reverses the three-way valve 66 and establishes communication between the waste-pipe 69 and the cylinders E F, exhausting the 110 water from the former and causing the piston-rod to return to its normal position. This downward movement of the piston-rod brings the lever 58 upon prism 57, moved in position, as above described, and the laterally-projecting weighted arm K' of the catch K, coming 115 in contact with the stop-pin n, projecting from the main frame A, disengages the catch from the regulating-fork 71, which is tilted back into its vertical position through the medium 120 of its weighted arm i', all the parts being thus again automatically brought into position for operation after having been automatically operated through the medium of an electro-magnet. 125

From what has been said above it will be observed that a standard clock may be regulated from an observatory by suitable electric connections, 81 82, between the electro-magnets T and the observatory-battery, and that 130 from this standard clock or direct from the observatory any number of clocks may be regulated.

If a series of clocks are to be regulated direct

from an observatory, the electro-magnets T of their regulating devices are all placed in the circuit of the observatory-battery through the medium of the wires 81 82. If the series of 5 clocks are to be regulated automatically from a standard clock, then the wires 81 and 82 of their electro-magnets T are connected with wires 48 and 49 of the standard clock, the circuit being closed through the medium of the 10 disk 46 on shaft 40 and its pins p^x and the contact-spring 47, the contact between the spring and pins occurring at every revolution of said disk or at every hour. In either case it is necessary to have at each secondary clock air- 15 compressing devices, both for regulating and winding up these clocks, or to have all the clocks connected by a net-work of pipes to convey either compressed air or a fluid to compress the air in the compressing devices. To 20 avoid this, I employ electro-pneumatic relays, which may be located at any distance from the standard clock. In locating these relays points are selected in proximity to a series of 25 clocks—for instance, a point in close proximity to several public buildings, each of which may be provided with any number of clocks connected pneumatically with the relay, and the latter electrically with the standard clock, thereby diminishing the expense of laying 30 networks of pipes and the loss of time or power by friction of the air within the pipes.

It will be further observed that the winding up of each clock may be effected automatically at the expiration of every hour by the appliances hereinbefore described. These appliances as applied to a standard clock may also be dispensed with at all the secondary clocks by the use of the relays. In its stead a mechanism much simpler in construction may be 40 employed, whereby the regulating and winding up of a series of secondary clocks may be effected simultaneously at each clock by the operation of a piston actuated by compressed air fed thereto from a suitable reservoir by the operation of said relay, as hereinafter described.

I will now proceed to describe the electro-pneumatic relay, referring more particularly to Figs. 10, 11, 12, 13, 14, and 15. These relays consist of a couple of electro-magnets, T', and an armature-lever, 85, connected at one end to a retracting-spring, 113, and at the other said lever carries a spring-pawl, 86, that engages with a ratchet, 87, and has a laterally-projecting pin, o' . The ratchet is pivoted upon a stand- 50 ard, N^2 , that also carries the pivoted and weighted pawl 88, that engages with said ratchet to prevent its retrograde movement.

Upon the ratchet 87 rides a lever, 89, pivoted upon an arm projecting from the stand- 55 ard, N^2 , its upper end carrying a prism, 90, which supports the outer end of a lever, 91, that has a pin, 93, working in a segmental slot, 94, formed in the rear horizontal arm of a three-armed lever, Q', the forward arm, 96, of 60 which terminates in a segment that carries the two stop-pins 97 and 98, which engage the

lever 99, a three-way valve, 100, interposed in the feed-pipe 101 102, and the waste-pipe 103. The lever Q' is further provided with a third vertical weighted arm that vibrates with said lever from one stop-pin, s^5 , to the other, s^6 , on the segment S³. The lever 91, which is pivoted upon the same shaft or stud as the lever Q', is connected with a piston-rod, 92, operating within a cylinder, G, connected through a feed-pipe, 106, with a three-way valve, U. This feed-pipe 106 is also connected with a cylinder, L', within which operates a piston, the rod 107 of which carries at its upper end a two-armed lever, Y, the laterally-projecting arm y' coming in contact with a pin, y^2 , on a pawl, 108, pivoted upon the standard N^2 , the nose of said pawl engaging a downwardly-projecting arm on the pawl 88, while the vertically-inclined arm of the pawl or lever Y is in a position to engage the pin o' on the pawl 86. The three-way valve U is interposed in a waste-pipe, 109, a supply-pipe, 105, connected with a compressed-air reservoir, I, and a pipe, 110, connected with the line-pipe that communicates with the secondary clocks. The valve-rod of said valve U is connected with one end of a lever, t, pivoted upon a standard, K', the other end of said lever being connected with a piston-rod, s⁷, the piston of which operates in a cylinder, H, connected with the feed-pipe 102.

N is a clock-case and clock-movement, of any desired or preferred construction, having a forked regulating-wing, a, upon the arbor t', that carries the hands. M is an air-cylinder connected with the line-pipe 110 and containing a compressible piston, m', to which is attached a forked bearing, h', that is moved up and down with said piston, the cylinder being slotted for the purpose, as shown, Figs. 13, 14, 105 and 15.

In the fork of the bearing h' lies the pin d' on the free end of a segmental lever, d, similar or nearly similar in construction and operating like lever 75 of the regulating mechanism, except that lever d is pivoted upon the axis of the winding-up drum, which also carries a ratchet, c, rigidly connected therewith, that is rotated by a spring-pawl, f, pivoted upon said lever d, a like pawl, e, preventing the retrograde movement of said ratchet. The lever d also carries a spring-pawl, g, adapted to engage the lower end of a sliding regulating or stop pin, b, arranged to move vertically and engage the regulating-fork a. When the lever d is in its normal position, Fig. 13, the pin b is supported upon the pawl g; but as the one end of the lever is raised by the piston-bearing h' the pawl gradually moves from under the pin until said lever has reached the 125 position shown in Fig. 14, when the regulating-pin will lie in the regulating-fork. A slight further upward movement of the piston causes the pawl to be disengaged from the pin, and the latter drops into the position 130 shown in Fig. 15. The lever end still continues to be raised until the air is exhausted

from the cylinder M, as hereinafter described, when it falls back into the position shown in Fig. 13, and the pawl g, through the medium of its spring, is again brought under the regulating-pin.

The automatic winding and regulating of secondary clocks, through the medium of the relays are as follows: At each complete revolution of the disk 46 on shaft 40, Fig. 5, of 10 the standard clock the contact-springs close the circuit with the electro-pneumatic relays through wires 48 49 and 83 84, which, as hereinbefore described, occurs at every hour, and the electro-magnets T' attract the armature-lever 85, thereby releasing lever 91 from prism 90 of lever 89 through the medium of the eccentric-ratchet 87. The lever 91, through its pin 93, tilts the lever Q' to establish communication between the feed-pipe 104, connected 15 with the compressed-air reservoir I and feed-pipe 102, in a manner similar to that of like devices on the regulating mechanism above described, thus admitting compressed air to the cylinder H. The influx of air to cylinder H raises 20 the piston and its rod, and through the lever t depresses the valve-rod to shift the three-way valve U and establish communication, through port V, between the feed-pipe 105, connected with the compressed-air reservoir I, the line-pipe 110, and pipe 106, connected with cylinder G L, and when these are about to reach the limit 25 of their upward movement the pawls 86 and 88 are disengaged from eccentric-ratchet disk 87 through the medium of the lever Y on piston-rod 107. The ratchet-disk 87, being thus liberated, is rotated back to its normal position by means of a spiral spring, (not shown in the drawings,) and causes the lever 89, carrying prism 90, to again assume a vertical position 30 to receive and support the lever 91. This latter lever at that moment has also reached the limit of its upward movement and tilted the lever Q' back from s⁵ to s⁶, thereby reversing the valve 100. The reversal of the valve 100 35 interrupts communication between the feed-pipe 104 and delivery-pipe 102, and establishes communication between the latter and the escape or waste pipe 103. The air from cylinder H escapes. The piston of the latter falls 40 back into its normal position, thereby raising the valve U to interrupt the communication between the feed-pipe 105, the connecting-pipe 106, and the line-pipe 110 and establish communication, through port w, between the latter 45 and the two pipes and the waste or escape pipe 109. The air from cylinders G and L' of the relays 50 and from cylinder M of the secondary clocks escapes and the parts return to their normal position of rest, which is that illustrated in 55 all the drawings, except the detail views and Figs. 14 and 15.

It will be evident that the mechanism and combination of mechanisms may be greatly varied, so far as their details of construction are 60 concerned, and other devices may be substituted for those chosen to illustrate the inven-

tion, but which I deem only as equivalents or substitutes.

It will also be seen that the mechanisms described may be set in operation by the breaking of the electric circuit—that is to say, they may be so arranged as to assume their normal positions of rest by the closing of the circuit, in which case the circuit is normally a closed one, instead of an interrupted one.

Having fully described my invention, what I desire to claim and secure by Letters Patent is—

1. The electric and hydropneumatic circuits connecting one or more groups of secondary 80 clocks with a standard clock, which consists of one or more groups of such secondary clocks in a corresponding series of pneumatic circuits, each of said circuits connected to and controlled by an electric relay interposed in 85 and the same electric circuit having its initial at the standard clock and its termini at the said relay or relays, as and for the purpose specified.

2. The combination, with the movement 90 and winding-up mechanism of a clock, a winding-pinion, a toothed winding-rod, actuated by air compressed through the medium of a liquid, and mechanism to feed the liquid to the air-compressing devices, of the hand-arbor 95 and devices to actuate the mechanism for feeding the liquid to the air-compressing devices whenever the minute-hand indicates the hour, as described.

3. The combination, with the winding-up 100 mechanism of a clock, a winding pinion and rod actuated by air compressed through the medium of a liquid, mechanism to feed the liquid to the air-compressing devices, and mechanism to actuate the feeding devices 105 whenever the minute-hand indicates the hour, of the tripping-rod 39 and levers 14 and 24, actuating a feed-valve to close said valve, as set forth.

4. The combination, with a clock-movement, 110 its winding mechanism, a winding pinion and rod actuated by air compressed through the medium of a liquid, and mechanism to feed the liquid to the air-compressing devices, of an actuating-pawl operated by the compressed 115 air that operates the winding-up devices to keep the clock-movement in operation during said winding up.

5. The combination, with a clock-movement, 120 its winding drum and pinion, a toothed winding-bar actuated by air compressed through the medium of a liquid, mechanism to feed the liquid to the air-compressing devices, a pawl actuated by the compressed air that operates the winding-up devices, and a toothed 125 wheel, P, on the main arbor of the clock-movement, of a reversing mechanism to stop the feeding of the liquid to the compressing devices, and mechanism to disengage the pawl from the wheel P when the clock is wound up, 130 for the purpose specified.

6. The combination, with the cord-drum and

its arbor, a winding-up pinion loosely mounted thereon, and a toothed winding-up bar actuated by air compressed through the medium of a liquid, of mechanism to feed the liquid to the compressing devices at predetermined periods, and mechanism to automatically lock the winding-up pinion to the arbor of the cord-drum as soon as the winding-up bar commences its upward movement, as set forth.

7. The combination, with the cord-drum and its arbor, a winding-up pinion loosely mounted thereon, a toothed winding-up bar actuated by air compressed through the medium of a liquid, mechanism to feed the liquid to the compressing devices at predetermined periods to compress the air and wind up the clock, and mechanism to lock the winding-up pinion to the drum-arbor, of a reversing mechanism to stop the feeding of the liquid, and mechanism to automatically disengage the pinion from the drum-arbor when the clock is wound up, as set forth.

8. The combination, with the cord-drum O, its arbor 40, the pinion 41, loosely mounted thereon, its spring-pawl 42, and the winding-up bar 37, actuating said pinion, of the cam 45 and devices to engage the pawl with the cam to lock the winding-up pinion to the drum-arbor, as and for the purpose set forth.

9. The combination, with the cord-drum O, its arbor 40, the pinion 41, loosely mounted thereon, its spring-pawl 42, and the winding-up bar 37, of the cam 45 and mechanism to disengage the pawl from the cam and the pinion from the drum-arbor, as and for the purpose specified.

10. The combination, with the three-way valve 30, the supply-pipe 111, delivery 32, the cylinders B C, the winding-up rod 37, the winding-up mechanism of the clock, the pawl 21, and intermediate mechanism for operating the valve through the medium of the pawl to admit water to the cylinder B for the purpose described, the rod 12, having stop 13, an enlargement 9, carrying roller 10, and prism 11, of the cam-disk 5 and the hands-arbor, substantially as described, and operating as and for the purpose set forth.

11. The combination, with the three-way valve 30, the supply-pipe 111, delivery-pipe 32, the cylinders B C, the winding-up rod 37, having stop 38, and the winding-up mechanism of the clock, of the rod 39, and the mechanism for reversing the valve to stop the flow of water to the cylinder B and exhaust the water therefrom, for the purpose specified.

12. The combination, with the three-way valve 30, the supply-pipe 111, the delivery-pipe 32, the cylinders B D, the piston and its rod 35, the lever 36, pawl r, the wheel P of the clock-movement, the winding-up mechanism, the pawl 21, and mechanism for operating the valve through the medium of said pawl to admit water to the cylinder B for the purpose described, the rod 12, having stop 13, and enlargement 9, carrying roller 10, and prism 11,

of the cam-disk 5 and the hands-arbor of the clock, substantially as described, and operating as and for the purpose specified.

13. The combination, with the three-way valve 30, the pipes 111, 27, and 32, the cylinders D B, the piston-rod 35, lever 36, pawl r, wheel P, and the winding-up mechanism of the clock, of the rod 39 and the mechanism for reversing the valve to stop the flow of water to and exhaust it from the cylinder B, substantially as described, and operating as and for the purpose specified.

14. The combination of the valve 30, having lever 29, and the operating-rod 12, having stop 13, with the pawl 21, lever 22, escapement-lever 18, and levers 14 and 25, all arranged, constructed, and operating substantially as and for the purpose specified.

15. In a clock, the combination, with the clock-movement, its winding-drum, the hands-arbor, and the regulating-arm thereon, of mechanism to automatically and simultaneously wind up and regulate the clock by means of air compressed through the medium of a liquid, a valve or valves automatically operated to admit liquid to the air-compressing devices, and mechanism to automatically reverse said valve or valves to arrest the flow of water to and exhaust it from the air-compressing devices when the clock is wound up and regulated and automatically return the winding and regulating mechanisms to their normal position, substantially as described.

16. In a clock, the combination, with the hands-arbor and a regulating-arm thereon, and a regulating fork or pin moving in the path of and arranged to engage said arm, of a piston-cylinder, a liquid-cylinder, a valve, and mechanism to shift said valve to admit a liquid to the liquid-cylinder, whereby the air in the latter and in the piston-cylinder is compressed to move the regulating fork or pin into engagement with the regulating-arm, as and for the purpose specified.

17. In a clock, the combination, with the hands-arbor and a regulating-arm thereon, and a regulating fork or pin moving in the path of and engaging said arm, of a piston-cylinder, a liquid-cylinder, a valve, and mechanism to shift said valve to exhaust the liquid from the cylinder, to move the regulating fork or pin out of engagement with the regulating-arm, substantially as and for the purpose specified.

18. In a clock, the combination, with the hands-arbor and a regulating-arm thereon, a regulating fork or pin, mechanism to move said fork or pin pneumatically into engagement with said arm, mechanism to trip the fork or pin out of engagement with the arm, and a valve to exhaust the motive fluid, of appliances to throw the regulating fork or pin back into its normal position in the path of the regulating-arm, as and for the purpose specified.

19. In a clock, the combination of the hands-arbor and a regulating-arm thereon, a piston and piston-rod carrying a pivoted regulating

- fork or lever moving in the path of said arm, means to admit compressed air to the piston or tripping mechanism to throw the regulating devices out of the path of the regulating-arm when the piston has reached or is about to reach the limit of its upward movement, a valve to exhaust the motive power from the piston-cylinder, and mechanism to return the regulating fork or lever into its normal position when the piston has reached or is about to reach the limit of its downward movement, all arranged and operating automatically, substantially as and for the purpose specified.
20. In a clock, the combination, with the hands-arbor carrying a regulating-wing, a regulating-fork moved in the path of said wing by means of air compressed through the medium of a liquid, a valve to admit the compressing medium to the compressing devices, and mechanism to operate said valve, of an armature-lever, an electro magnet, and suitable connections with a battery, whereby said devices are set in operation electrically, substantially as and for the purpose specified.
25. 21. In a clock, the combination, with the hands-arbor carrying a regulating-wing, a regulating-fork moved in the path of said wing by means of air compressed through the medium of a liquid, a valve to admit the compressing medium to the compressing devices, mechanism to operate said valve, and a tripping mechanism to throw the regulating-fork out of the path of the regulating-wing when said fork has reached or is about to reach the limit of its movement in one direction, of an armature-lever, an electro magnet, and suitable connections with a battery, whereby said devices are set in operation electrically, substantially as and for the purpose specified.
30. 22. In a clock, the combination, with the hands-arbor, its regulating-wing, a regulating-fork reciprocating in the path of said wing by means of air compressed through the medium of a liquid, a valve to admit the compressing medium to or exhaust it from the compressing devices, mechanism to operate said valve, and tripping mechanisms to throw the regulating-fork into or out of the path of the regulating-wing, of an armature-lever, an electro-magnet, and suitable battery-connections, whereby said devices are set in operation electrically, substantially as and for the purpose specified.
35. 23. The combination, with the regulating-wing 7, the piston-rod 70, and its pivoted fork 71, having bracket *i*, of the hooked rod *j*, substantially as and for the purpose specified.
40. 24. The combination, with the regulating-wing 7, the piston-rod 70, and its pivoted fork 71, having bracket *i*, of the hooked rod *j* and spring-catch *k*, substantially as and for the purpose specified.
45. 25. The combination, with the regulating-wing 7, the piston-rod 70, its pivoted fork 71, having bracket *i*, and the spring-catch *k*, of the stop *n* in the path of said spring-catch, for the purpose specified.

26. The combination, with the regulating-wing 7, the piston-rod 70, its stop-arm *m*, and the pivoted fork 71, having bracket *i*, of the weighted and hooked rod *j*, substantially as and for the purpose specified.

27. The combination, with the feed, delivery, and exhaust pipes, the valve 66, and the lever 58 of the valve-shifting mechanism, of the electro-magnet, the armature-lever 50, its spring 112 and pawl 51, the ratchet 52, eccentric 55, and the lever 56, all arranged and operating substantially as described, for the purpose specified.

28. The combination, with the feed, delivery, and exhaust pipes, the valve 66, and the lever 58 of the valve-shifting mechanism, of the rods 72, 73, and 74, the pawl-lever 75, the weighted pawl L², pawl 53, the armature-lever and its pawl 51, the ratchet 52, eccentric 55, and the lever 56, all arranged and operating substantially as and for the purpose specified.

29. The combination, with the clock-regulating devices, the piston-rod 70, the cylinders F 90 E, the delivery, feed, and exhaust pipes, the valve 66, and the lever 58 of the valve-shifting mechanism, of the electro-magnet, the armature-lever and its pawl 51, the ratchet 52, pawl 53, eccentric 55, and the lever 56, all arranged and operating substantially as and for the purpose specified.

30. The combination, with the clock-regulating devices, the piston-rod 70, the cylinders F E, the delivery, feed, and exhaust pipes, the valve 66, and the lever 58 of the valve-shifting mechanism, of the armature-lever 50, its pawl 51, the rods 72, 73, and 74, the levers 75 100 76, the pawl 53, eccentric 55, and lever 56, all arranged and operating substantially as described, for the purpose specified.

31. An electro-pneumatic relay interposed between an electric and a pneumatic circuit connecting a series of secondary clocks with a standard clock, substantially as and for the purpose specified.

32. An electro-pneumatic relay interposed in an electric pneumatic circuit, electrically connecting a standard clock and a series of secondary clocks, for the purpose specified.

33. The relay, substantially as described, consisting of a valve interposed in the compressed-air exhaust, feed, and line pipes, an electro-magnet, and an armature-lever operating a shifting mechanism to shift said valve 120 to admit compressed air to the line-pipe, forming the pneumatic circuit, substantially as and for the purpose specified.

34. The combination, with a series of clocks arranged within a pneumatic circuit and provided with winding-up mechanism actuated pneumatically, of an electro-pneumatic relay consisting of two valves interposed in the feed and line pipes, mechanism to shift said valves to admit the air to the winding-up mechanism 125 of the clocks within the circuit and wind up said clocks simultaneously, and an electro-

magnet and armature-lever to set the valve-shifting devices in operation electrically, substantially as and for the purpose specified.

35. The combination, with a series of clocks arranged within a pneumatic circuit, and provided with winding-up mechanisms actuated pneumatically, of an electro-pneumatic relay consisting of two valves interposed in the feed and line pipes, mechanism to shift said valves to cut off the flow of compressed air to the winding-up mechanisms after the winding up is completed, and an electro-magnet and armature-lever to set the shifting devices in operation electrically, substantially as set forth.

15 36. The combination, with a series of clocks arranged within a pneumatic circuit, winding-up mechanism, and mechanism for returning the winding-up devices into their normal position, all operated pneumatically, of an electro-pneumatic relay consisting of two valves interposed in the compressed-air exhaust, feed, and line pipes, and mechanism to shift said valves to stop the flow of air to and exhaust it from the winding mechanism to arrest the 20 further winding up and return said mechanisms simultaneously into their normal position, substantially as described.

37. The combination, with a series of clocks arranged within a pneumatic circuit, and regulating mechanism for each of said clocks, operated pneumatically, of an electro-pneumatic relay consisting of two valves interposed in the feed and line pipes, mechanism to shift said valves to admit compressed air to said 35 line-pipe, and regulating mechanism to regulate all the clocks within the circuit simultaneously, an electro-magnet, and an armature-lever to set the valve-shifting devices in operation electrically, substantially as described.

40 38. The combination, with a series of clocks arranged within a pneumatic circuit, and regulating mechanism for each of said clocks, operated pneumatically, of an electro-pneumatic relay consisting of two valves interposed in the feed and line pipes, mechanism to shift said valves to stop the flow of compressed air to said line-pipe and to the regulating mechanisms, and to arrest the further winding up of all the clocks within the circuit simultaneously, an armature-lever and its retracting-spring, and an electro-magnet to set the valve-shifting mechanism in operation electrically, substantially as set forth.

39. The combination, with a series of clocks arranged within a pneumatic circuit, regulating mechanism, and mechanism to return the regulating devices into their normal positions for each clock, of an electro-pneumatic relay consisting of two valves interposed in the exhaust, feed, and line pipes to stop the flow of compressed air to and exhaust it from the regulating devices and return said devices to their normal position at all the clocks simultaneously, an electro-magnet, an armature-lever, and a retracting-spring for said lever to set the valve-shifting devices in operation electrically, substantially as set forth.

40. The combination, with a series of clocks arranged within a pneumatic circuit, and winding-up and regulating mechanisms for each clock, operated pneumatically, of an electro-pneumatic relay consisting of two valves interposed in the feed and line pipes to admit compressed air to the winding-up and regulating mechanisms to operate the same simultaneously in all the clocks, mechanism to shift said valves, an electro-magnet, and an armature-lever to set the valve-shifting mechanism in operation electrically, substantially as set forth.

41. The combination, with a series of clocks arranged within a pneumatic circuit, and winding-up and regulating mechanism for each clock, operated pneumatically, of an electro-pneumatic relay consisting of two valves interposed in the feed, line, and exhaust pipes to stop the flow of compressed air to and exhaust it from the winding and regulating devices, to stop the winding and regulating simultaneously at all the clocks within the circuit, mechanism to shift said valves, an electro-magnet, an armature-lever, and a retracting-spring for said lever to set the valve-shifting mechanism in operation electrically, as set forth.

42. The combination, with a standard clock and a series of secondary clocks arranged within an electric circuit, and mechanism to wind up and regulate and return the winding-up and regulating mechanisms into their normal positions, operated pneumatically, of an electro-pneumatic relay consisting of two valves interposed in the feed, line, and exhaust pipes, mechanism to shift said valves to cut off the flow of compressed air to and exhaust it from the regulating and winding mechanism, and return the same into their normal position simultaneously at all the clocks within the circuit, an electro-magnet, an armature-lever, and its retracting-spring to set the valve-shifting mechanism in operation electrically, substantially as set forth.

43. The combination, with a series of clocks arranged within a pneumatic circuit, each provided with a regulating and winding-up mechanism, and a standard clock arranged within an electric circuit, of an electro-pneumatic relay, interposed in the said electric and pneumatic circuits, consisting of an electro-magnet, an armature-lever in the electric circuit, the valves 100 and V in the pneumatic circuit, and intermediate mechanisms to operate said armature-lever from the standard clock, and the valves from the armature-lever to automatically and simultaneously wind up and regulate all the clocks within the pneumatic circuit through the medium of the standard clock, as set forth.

44. The combination, with the pneumatically-operated winding-up and regulating mechanism of a clock or clocks arranged within a pneumatic circuit, an electro-magnet, an armature-lever, a valve interposed in the feed and delivery pipe, and intermediate mechanism to shift said valve through the medium of the vibrations of said armature-lever, of a

secondary valve and shifting mechanism interposed in the delivery and line pipe to admit compressed air to the regulating and winding-up mechanism of the clock or clocks within the circuit, and to simultaneously operate shifting mechanism of the primary valve to stop the flow of air to the secondary valve, and through the medium of the latter exhaust the air from the line-pipe, as and for the purpose set forth.

45. The combination, with the electro-magnet, its armature-lever, the valve 100, and intermediate mechanism to shift said valve, and the pipes 104 and 102, of the cylinder H, its piston and piston-rod s' , the lever t , the valve-rod and valve V, and the line-pipe 110, all operating substantially as described, for the purpose specified.

46. The combination of the electro-magnet, its armature-lever, the valve 100, and intermediate mechanism to shift said valve, and the pipes 104, 103, and 102 of the cylinder H, the valve V, and intermediate mechanism to shift said valve, the pipe 106, the cylinders G L', their pistons 92 107, and the mechanism for shifting the valve 100, all operated substantially as and for the purpose specified.

47. The combination, with the valve 100, the electro-magnet and its armature-lever carrying the pawl 86, the retracting-spring 113 for said lever, and the valve 100, having valve-lever 99, of the partially-toothed eccentric disk or cam 87, the pawl 88, prism-lever 89, and the levers 91 and Q', all constructed, arranged, and operating substantially as and for the purpose specified.

48. The combination, with the pipes 101, 103, and 102, the valve 100, the electro magnet, its armature-lever 85, having pawl 86, and spring 113, of the cylinder H, valve V, the intermediate shifting mechanism for shifting said valve, the pipe 106, cylinder G, piston 92, levers 93 and Q', cylinder L', piston 107, terminating in a forked lever, the partially-toothed cam 87, pawls 88 108, and the lever 90, all arranged and operating substantially as and for the purpose specified.
